UNITED STATES PATENT OFFICE.

JOHN P. POMEROY, OF GREAT BARRINGTON, AND HENRY M. VAN DEUSEN,
OF WESTFIELD, MASSACHUSETTS.

DESIGN FOR A WHIP-LOAD.

SPECIFICATION forming part of Design No. 32,438, dated April 3, 1900.

Application filed February 24, 1900. Serial No. 6,420. Term of patent 14 years.

To all whom it may concern:

Be it known that we, JOHN P. POMEROY, residing at Great Barrington, in the county of Berkshire, and HENRY M. VAN DEUSEN, residing at Westfield, in the county of Hampden, State of Massachusetts, citizens of the United States, have invented and produced a new and original Design for Whip-Loads, of which the following is a specification.

Our invention relates to designs for loads for whips adapted to be applied to the butt-end of a whip-stock.

In the accompanying drawings, which form a part of this specification, Figure 1 is a side view of a whip-load, showing our new design. Fig. 2 is a central longitudinal section thereof.

The leading feature of our design is a series of beads formed on the outer surface of the load and a ball connected to one of the end beads. The load is circular in cross-section.

What we claim is—

The design for a whip-load, substantially as shown and described.

In testimony whereof we have hereunto set our hands in presence of two subscribing witnesses.

JOHN P. POMEROY.

HENRY M. VAN DEUSEN.

Witnesses:

AMY N. STILES,
M. A. WILLIAMS.
